UNITED STATES PATENT OFFICE.

ALBERT H. STEBBINS, OF LOS ANGELES, CALIFORNIA.

CONCENTRATOR DECK.

Application filed June 14, 1926. Serial No. 115,818.

This invention relates to concentrator decks, and more particularly to means adjacent the feed hopper for guiding the materials from the hopper onto different portions of the deck surface.

The transversely inclined concentrator decks as constructed heretofore have been provided with feed hoppers that deliver the materials to be treated to the upper side of the deck or to an end thereof near the upper side of the deck. The materials are delivered to the upper portion of the deck in order that their separation may be effected as they work downwardly across the inclined deck.

The constructions employed heretofore whereby the materials to be treated are delivered to a relatively small portion of the deck surface near the upper side or upper end portion of the deck are objectionable, because, they produce an excessive volume of materials in the small area of the deck near the feed hopper, and in order to disseminate these materials over the deck surface it has been necessary to employ more force than is needed to classify and stratify the materials after they have been spread out over the deck surface.

The materials delivered to the deck surface by the feed hopper have been spread out over the deck surface heretofore by vibrating the deck, by imparting a transverse inclination to the deck, and by forcing air upwardly through the materials, but, as above stated, the force which it has been necessary to employ heretofore to work the materials away from the feed hopper has in many cases been too strong to effect the desired separation of the materials upon the deck surface.

The present invention therefore relates to a novel construction for directing the materials to be treated from the feed hopper to predetermined positions upon the deck surface, and a primary feature of the present invention resides in a concentrator deck having a series of tall guide walls that extend from the feed hopper over a portion of the deck surface, and which are arranged to form canyons in which the materials flow to predetermined positions upon the deck surface.

The tall guide walls preferably extend diagonally over the deck surface in a direction to direct the materials toward the upper side of the deck, and as a result of this construc-

tion the materials may be supplied to the deck surface by a hopper that extends across the entire end of the deck, or which is disposed at the end of the deck near the lower side thereof. The canyons formed between the high guide walls serve not only to direct the materials to different predetermined positions upon the deck surface, but also to effect a partial stratification of the materials as they travel along the canyons.

As a result of the present invention, the difficulty experienced heretofore in working the materials away from the feed hopper is overcome, and the materials are delivered by the high walls to the desired portions of the deck surface in a partially treated condition. Furthermore, the points at which the materials leave the canyons are sufficiently spread out over the deck surface to permit the materials to be rapidly treated upon the remaining portion of the deck surface.

The various features of the invention will be best understood from the following description when read in connection with the accompanying drawings, wherein:

Fig. 1 is a perspective view of a concentrator deck constructed in accordance with the present invention;

Fig. 2 is a top plan view of the deck of Fig. 1;

Fig. 3 is a plan view of a modified type of deck; and

Fig. 4 is a plan view of a combined guide wall and riffle.

The concentrator deck embodying the features of the present invention may for the most part have the usual or any preferred construction, and in the construction shown the concentrator deck is provided with a concentrate wall 10 having the usual buffer blocks 11 against which the concentrates are directed by the inclined riffles to be described. The materials to be treated are delivered to the deck surface 12 which may have apertures 13 formed throughout its entire surface; or formed in only a portion of the deck surface, as desired. The concentrator deck may have the usual air chamber 14 provided below the deck surface, and to which air under pressure may be supplied by a fan blower 15, the discharge portion of which blower is connected to a hood 16 of the deck by the flexible connection 16a.

The concentrator deck is preferably supported at a transverse inclination, as shown in Fig. 1, and to this end the deck is mount-

ed upon the supporting carriage 17, the lower or trailing discharge side of the deck being secured to the carriage by the hinges 18 while the upper or concentrate side of the deck is supported in spaced relation to the carriage as is usual. The deck is preferably mounted for vibratory movement in the direction of its length, and while various means might be provided for supporting the deck so that it may partake of such movement, the means shown consists of the bearing blocks 19 that are mounted upon the deck supporting frame, and each of these bearing blocks is provided with a recess adapted to receive a ball or roller 20 the upper portion of which extends into a similar bearing block 21 which is secured to the under face of the carriage 17. The supporting frame may be constructed of the uprights 22 which are connected by the longitudinally extending beams 23 and the uprights at the opposite sides of the concentrator may be connected by the transversely extending braces 24. The bearing blocks 19 may be mounted at the upper ends of the uprights 22.

In most cases it will be desirable to impart a progressive vibratory movement to the concentrator deck, and while various means might be employed for imparting a progressive movement to the deck, the means shown to this end consists of the spring actuated cables 25, two being shown, which serve to pull the deck in the right-hand direction, and power operated cables are provided for pulling the deck in the left-hand direction. Each of the cables 25 has one end secured to a bar or tube 26 that may be clamped to a bracket 27 fastened to a transversely extending brace 28 of the supporting carriage 17. Each cable 25 passes around a grooved sheave 29 which is rotatably supported by a transversely extending shaft 30 the ends of which are mounted in bearing brackets supported by the main frame. Each cable 25 extends from this sheave 29 downwardly and has its lower end attached to a coiled spring 31 the upper face of which spring rests against a transversely extending bar 32. The arrangement is such that the compressed springs 31 exert a constant pull upon the cables 25 to urge the deck in a right-hand direction.

The means shown for moving the deck in a left-hand direction consists of the cables 33, two being shown, and each of these cables has one end fastened to a bracket 27 which is fastened to a transversely extending brace 28 of the carriage, and the adjacent ends of the cables 25 and 33 may be connected by a turn buckle 34 so that the pull of one cable will be transmitted directly to the other. Each cable 33 extends around a grooved sheave 35 which is rotatably supported by a transversely extending shaft 36,

and which may be similar to the sheave 29 above described. The cables 33 pass from the sheaves 35 downwardly and around the grooved sheaves 37 which are mounted upon the eccentrics 38, and the lower portion of each cable 33 is anchored to the machine supporting frame by a bolt 39 which may be adjusted to vary the effective length of the cables 33. The eccentrics 38 are constructed to rotate within the sheaves 37 and they are rigidly secured to the main shaft 40 which may be driven by a pulley not shown. The arrangement is such that rotation of the shaft 40 will cause the eccentrics 38 to rotate within the sheaves 37, to move these sheaves in an orbital path. This movement of the sheaves will serve to alternately tension and slack off the cables 33 so that as these cables are tensioned they will pull the deck in a left-hand direction, and as they are slackened off they will permit the deck to move in a right-hand direction under the action of the springs 31. By varying the strength of the springs 31 the progressive movement imparted to the deck may be made as energetic as desired.

The construction so far described forms no essential part of the present invention, but is shown to make clear the novel features of the invention which will now be described. The materials to be treated are delivered to the deck surface by the hopper 41, and it should be noted that this hopper is shown as extending across the entire left-hand end of the deck. The materials flow from the hopper on to the deck surface by passing through an opening provided between the lower edge of the wall 42 and the bottom of the hopper.

As stated, difficulty has been experienced heretofore in devising satisfactory means for working the materials away from the hopper and spreading them out over the deck surface, without imparting to the deck forces that are more energetic than are desired to effect the separation of the materials after they have been worked away from the hopper. This difficulty is overcome in accordance with the present invention by providing adjacent the hopper 41 a series of guide walls 43 which extend from the feed hopper over the deck surface to form relatively deep canyons in which the materials travel to the desired portion of the deck surface. These guide walls 43 are given a sufficient height to prevent the materials from flowing transversely over the walls from one canyon into another, and the guide walls preferably extend diagonally over the deck surface as shown, so that they serve to direct the materials up the transversely inclined deck surface as the materials travel along the canyons formed between the high walls 43. These walls 43 preferably increase in length in the direction in which they are

arranged along the feed hopper towards the lower side of the deck, as will be apparent from the drawings; this being desirable so that the canyons formed between the walls will direct the materials traveling in these canyons to different portions of the deck surface to thereby spread out the materials sufficiently to enable them to be rapidly concentrated after they leave the canyons.

The high guide walls 43 serve not only to direct the materials away from the feed hopper and to spread them out over the deck surface, but also to confine the materials while a preliminary stratification of these materials is being effected as they travel along the canyons. The use of the guide walls 43 permits the employment of a feed hopper 41 that extends across the entire end of the concentrator deck, as shown, since by arranging the walls 43 so that they extend from the feed hopper towards the upper side of the deck they direct the materials within the canyons towards the upper side of the deck.

That portion of the deck surface 12 which is not provided with the guide walls 43 may be provided with the usual inclined riffles 44, and after the materials leave the canyons they may be treated upon the remaining portion of the deck surface in the usual manner. That is, the concentrates will travel along the riffles 44 towards the concentrate wall while the lighter materials or tailings will gradually work up over the concentrates and flow laterally over the riffles 44 towards the lower side of the deck under the influence of the transverse slope of the deck surface. The guide walls 43 and riffles 44 may be formed separately, or, if desired, they may be formed of a single strip of metal or other material, as shown in Fig. 4, and if desired the riffles 44 may be given the tapered construction shown in Fig. 4 so that their height gradually decreases as they approach the concentrate wall.

The progressive movement imparted to the deck will help classify the materials traveling within the canyons and the classification of these materials may be further effected by forming the apertures 13 in the deck surface between the walls 43 to subject the materials to the separating action of rising air currents. These apertures may be formed only in that portion of the deck lying near the feed hopper, as shown in the modification of Fig. 3, or they may be formed in the entire deck surface, as shown in Figs. 1 and 2. The tall guide walls 43 may be arranged in alignment with the riffles 44, as shown in Figs. 1 and 2, so that these guide walls are placed as close together as are the riffles, or if desired the space between the adjacent guide walls 43 may be greater than the space between the riffles, as shown in Fig. 3, wherein it will be seen

that a riffle 44 lies between each pair of adjacent walls 43. Since the guide walls extend transversely over the deck surface the wall extending along the lower side of the deck surface may be deflected inwardly, as indicated by 45 in Figs. 1 and 2, or if desired several additional guide walls 43 may be provided along the lower wall 46 of the concentrator deck as shown in Fig. 3. These additional walls which do not communicate with the hopper 41 of Fig. 3 it will be understood do not receive materials from the discharge hopper, but the right-hand ends of these walls serve to prevent the materials from flowing too rapidly over the riffles towards the lower side of the deck.

It will be apparent from the foregoing that the guide walls 43 serve to deliver to the upper side of the deck the amount of materials that can be properly handled there and to deliver to other portions of the deck disposed progressively down the deck surface the amount of material that can be best taken care of upon each portion of the deck. As a result of this construction the materials are not only spread out over the deck surface by the guide walls so that they may be rapidly separated as they travel along the riffles, but the speed at which the separation of the materials may be effected upon the remaining portion of the deck is greatly increased, due to the fact that the materials are in a partially stratified condition when they issue from the canyons. It will therefore be seen that the guide walls 43 forming the subject matter of the present invention not only constitute an extremely satisfactory means for directing the materials away from the feed hopper over the deck surface, but that they also materially increase the speed at which the materials may be concentrated upon the deck surface. The dotted line 47 shown in Figs. 2 and 3 is provided merely to indicate the approximate field of the different zones; that is, that portion of the deck surface lying above the dotted line 47 is the portion of the deck surface in which the concentrates predominate, while the portion of the deck surface lying below this line is the portion of the deck surface in which a rapid cross flow of the tailings is being effected.

What is claimed is:—

1. A concentrator deck, comprising in combination, a deck casing having a deck surface that is supported at a transverse inclination, diagonally disposed riffles upon the deck surface and arranged to direct the concentrates toward the upper side of the deck while the tailings flow over the riffles toward the lower side of the deck, a feed hopper at one end of the deck, and a series of guide walls extending from the hopper over the deck surface toward the upper side of the deck and arranged to form canyons in which

the material flows to predetermined portions of the deck surface, said walls having sufficient height to prevent the materials from flowing laterally over the walls.

2. A concentrator deck, comprising in combination, a deck casing having a deck surface that is supported at a transverse inclination, riffles upon the deck surface for separating the concentrates from the tailings, a feed hopper at one end of the deck, and a series of guide walls extending from the feed hopper toward the upper side of the deck and arranged to form canyons in which the materials flow to predetermined portions of the deck surface, said walls being of sufficient height to prevent the materials from flowing laterally over the walls.

3. A concentrator deck, comprising in combination, a deck casing having a deck surface that is supported at a transverse inclination, riffles upon the deck surface for separating the concentrates from the tailings, a feed hopper at one end of the deck, a series of guide walls extending from the feed hopper toward the upper side of the deck and arranged to form canyons in which the materials flow to predetermined portions of the deck surface, said walls being of sufficient height to prevent the materials from flowing laterally over the walls, and means for vibrating the deck to effect a preliminary classification of the materials as they travel in said canyons.

4. A concentrator deck, comprising in combination, a deck casing having a deck surface that is supported at a transverse inclination, a feed hopper at one end of the deck, a series of guide walls extending from the hopper over the deck surface toward the upper side of the deck and arranged to form canyons in which the materials flow to predetermined portions of the deck surface, said walls being of sufficient height to prevent the materials from flowing laterally over the walls, and riffles extending from the delivery ends of the canyons over the deck surface.

5. A concentrator deck, comprising in combination, a deck casing having a deck surface that is supported at a transverse inclination, a feed hopper at one end of the deck, a series of guide walls extending from the hopper over a portion of the deck surface and arranged to form canyons between them in which the materials flow to predetermined portions of the deck surface, said walls being of sufficient height to prevent the materials from flowing laterally over the walls, and the deck surface between said walls being apertured to subject the

materials flowing in the canyon to the separating action of rising air currents.

6. A concentrator deck, comprising in combination, a deck casing having a deck surface that is supported at a transverse inclination, a feed hopper at one end of the deck and having a portion adjacent the lower side of the deck, a series of guide walls extending from the feed hopper diagonally over the deck surface and arranged to form canyons in which the materials flow up the inclined deck surface to predetermined positions thereupon, and the walls being of sufficient height to prevent the materials from flowing laterally over the walls.

7. A concentrator deck, comprising in combination, a deck casing having a deck surface that is supported at a transverse inclination, a feed hopper at one end of the deck, a series of guide walls extending from the feed hopper diagonally over the deck surface and arranged to form canyons in which the materials flow to predetermined positions upon the deck surface, said walls having a sufficient height to prevent the materials from flowing laterally over the walls and having their length increased in the order in which they are arranged from the upper to the lower side of the deck.

8. A concentrator deck, comprising in combination, a deck casing having a deck surface that is supported at a transverse inclination, a feed hopper at one end of the deck, riffles extending diagonally over the deck surface so that they slope upwardly toward the upper side of the deck, and the riffles lying near the feed hopper being provided with relatively high walls over which the materials will not flow laterally and said walls being arranged to form canyons between them which guide the materials from the hopper to predetermined positions upon the deck surface.

9. A concentrator deck, comprising in combination, a deck casing having a deck surface that is supported at a transverse inclination, a feed hopper at one end of the deck, a series of guide walls extending from the hopper in an inclined direction up the deck surface and arranged to form canyons in which the materials flow in an inclined direction up the deck surface to predetermined portions of the deck surface, and said walls being of sufficient height to prevent the materials from flowing laterally over the top of the walls.

In testimony whereof, I have signed my name to this specification.

ALBERT H. STEBBINS.
